CLAIM

The ornamental design for a threaded lug nut cover with jewel, as shown and described.

DESCRIPTION

FIG. 1 is a rear side perspective view of the threaded lug nut cover with jewel, showing my new design;

FIG. 2 is a front side perspective view thereof;

FIG. 3 is a front view thereof;

FIG. 4 is a rear view thereof;

FIG. 5 is left side view thereof;

FIG. 6 is a right side view thereof;

FIG. 7 is a top view thereof; and,

FIG. 8 is a bottom view of the threaded lug nut cover with jewel.
